(57) **CLAIM**

The ornamental design for a precious stone jewelry setting, as shown and described.

DESCRIPTION

FIG. 1 is a perspective view of a precious stone jewelry setting showing my new design.

FIG. 2 is a front view of FIG. 1.

FIG. 3 is a right side view of FIG. 1, the left side being symmetrical; and,

FIG. 4 is a rear view of FIG. 1.

The broken lines shown in the drawings illustrate environmental structure that forms no part of the claimed design.
